SUPPORT STAND FOR A TELEVISION RECEIVER

Richard E. Lee, Cazenovia, N.Y., assignor to General Electric Company, a corporation of New York

Filed Nov. 23, 1962, Ser. No. 72,591

Term of patent 7 years

(Cl. D33—3)

FIG.1

FIG.2

FIGURE 1 is a perspective view of a support stand for a television receiver showing my design; and

FIGURE 2 is a side elevational view on a reduced scale.

I claim:

The ornamental design for a support stand for a television receiver, as shown.
